UNITED STATES PATENT OFFICE.

WILLIAM LEE GRIFFIN, OF DALLAS, NORTH CAROLINA.

AUTOMATIC GRADE-CROSSING BLOCK.

Application filed September 16, 1922. Serial No. 588,672.

To all whom it may concern:

Be it known that I, WILLIAM LEE GRIFFIN, a citizen of the United States, residing at Dallas, in the county of Gaston and

5 State of North Carolina, have invented new and useful Improvements in Automatic Grade-Crossing Blocks, of which the following is a specification.

This invention relates to a railroad crossing gate, the general object of the invention being to provide means whereby the train approaching the crossing will lower the gate and will operate means to raise the gate after it passes the crossing.

10 Another object of the invention is to provide fluid actuated means for moving the gate.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a plan view showing a portion of a railroad track and a crossing with my invention in use.

Figure 2 is a side view.

35 Figure 3 is a section on line 3—3 of Figure 1.

Figure 4 is a section on line 4—4 of Figure 1.

Figure 5 is a perspective view of the 40 trip operated catch and its shaft and segmental gear.

Figures 6 and 7 are views showing the means for holding the parts retracted, figure 6 showing the means at the front end of the trip rod 32 and Figure 7 shows the means at the rear end of such rod.

45 Figure 8 is a detail view of the means for ringing a bell by the movement of the gate.

In these views A indicates the track and 50 B the crossing. Each gate 1 is carried by a post 2, the gate being provided with a counter weight 3 as usual. A cylinder 4 is placed adjacent the gate, said cylinder having a piston 5 therein, the rod 6 of which 55 being connected by a universal joint 7 with a cranked rod 8 which is connected with

the rear end of the gate. A spring seat 9 is carried by the piston rod and a spring 10 is placed on the seat. The forked end of a rod 11 engages the upper end of the 60 spring and the lower end of the rod is connected by the universal joint 12 with a bell crank 14 which is pivoted at 15 to the base 16. One arm of the bell crank carries an adjusting bolt 17 which is adapted to be 65 engaged by the push rod 18 which is eccentrically connected to a disc 19 carried by the shaft 20 which is journaled to one of the ties of the track. This shaft carries the segmental gears 21 which are adapted 70 to be engaged by the spring trip 22 which is carried by a part of the train. A cylinder 23 is placed at each side of the crossing an appreciable distance therefrom and each cylinder 23 is connected with the cylinder 4 by means of the pipes 24 which contain the valves 25. The cylinder 23 contains a piston 26 which is normally held in its forward position by a spring 27 within the cylinder. A catch 28 is connected 75 with the piston and this catch is adapted to engage a catch 29 on a stub shaft 30 which is suitably journaled to a part of the track, the catches when in engagement acting to hold the piston in retracted position. A segmental gear 31 is attached to the shaft 30 and this gear is adapted to be 80 engaged by the trip 22 on the train so as to release the catches to permit the springs 27 to force the piston 26 forwardly. The parts 85 are retracted by means of the spring controlled trip rods 32 suitably supported by parts of the track, each of said rods carrying a latch 33 for engaging a keeper 34 on the shaft 20 to hold the same in the 90 position to which it is moved by the trip 22 on the train, the other end of the rod having a slot 35 therein which is engaged 95 by a projection 36 on the rod 37 which connects the piston 26 with the catch 28. 100

The cylinders are to contain a supply of oil or the like, the major part of the oil being drawn into the cylinder 23 when the piston 26 is retracted. When a train approaches a crossing the trip 22 engaging the segmental gear 31 will release the catches, thus permitting the spring 27 to force the piston 26 forwardly so as to force the oil in the cylinder 23 through the pipe 24 into the cylinder 4. Thus the piston 5 in the cylinder 4 110 will be raised and this movement of the pistons will be transmitted to the gate so as to

lower the same. As a train passes over the crossing the trip 22 will engage one of the segmental gears 21 on the shaft 20 so as to rock the shaft and thus cause the push rod 5 18 to engage the bell crank which will act to pull the forked rod 11 downwardly, thus contracting the spring 10 and thus causing the piston 5 to force the oil in cylinder 4 back into the cylinder 23. This oil will 10 force the piston 26 rearwardly and thus place the catches 28 and 29 into engagement again. Near the end of this movement the projection 36 will engage the rear wall of the slot 35 thus moving the rod 32 to cause 15 its latch 33 to disengage the keeper 34 and thus permit the spring 10 to return the parts to normal position. Thus the gate will be opened and closed automatically by the train.

20 I may also provide an alarm which consists of a bell 40 on the gate post, the hammer 41 of which being actuated by a rack bar 42 which is connected with the gate so that as the gate is moving upwardly and 25 downwardly the hammer will be actuated to strike the bell.

It is thought from the foregoing description that the advantages and novel features of my invention will be readily apparent.

30 I desire it to be understood that I may make changes in the construction and in the combination and arrangement of the several parts, provided that such changes fall within the scope of the appended claims.

35 What I claim is:—

1. In combination with a barrier for a railroad crossing, a cylinder, a piston therein connected with the barrier, a cylinder placed at each side of the crossing, pipes 40 connecting the cylinders together, said cylinders containing a fluid, a piston in each of the other cylinders, a spring for forcing each of said pistons forwardly, latch means for holding the pistons in retracted position, 45 means on the train for releasing the latch means so as to permit the springs to force the pistons forwardly and thus expel the oil

from the track cylinder into the gate cylinder and means located adjacent the crossing and actuated by the train for returning the parts to normal position. 50

2. In combination with a barrier for a railroad crossing, a cylinder, a piston therein connected with the barrier, a cylinder placed at each side of the crossing, pipes connecting the cylinders together, said cylinders containing a fluid, a piston in each of the other cylinders, a spring for forcing each of said pistons forwardly, latch means for holding the pistons in retracted position, 55 means on the train for releasing the latch means so as to permit the springs to force the pistons forwardly and thus expel the oil from the track cylinder into the gate cylinder, means located adjacent the crossing and actuated by the train for returning the parts to normal position, such means consisting of a spring for returning the piston of the gate operating cylinder to its lowered position, and train operated means for applying pressure to the spring. 60

3. In combination with a barrier for a railroad crossing, a cylinder containing fluid, a piston therein connected with the barrier, a track cylinder, pipes connecting the cylinders together, a spring pressed piston in the track cylinder, latch means for holding the piston in retracted position, means on the train for releasing the latch means, a spring associated with the barrier piston for lowering the same when the spring is compressed, a compression member for the spring, a shaft located adjacent the crossing and adapted to be rocked by the passage of a train, a push bar actuated by the shaft for causing the compression member to compress the spring, trip means for holding the shaft in the position to which it has been moved by the train and means associated with the track cylinder for releasing the trip means. 75 80 85 90 95

In testimony whereof I affix my signature.

WILLIAM LEE GRIFFIN.
